(57) **CLAIM**

The ornamental design for a plug-in heater for hot curlers, as shown and described.

DESCRIPTION

FIG. 1 is a perspective view of the heater embodying the new design with the plugs in a storage position;

FIG. 2 is a front elevational view thereof;

FIG. 3 is a top plan view thereof;

FIG. 4 is a rear elevational view thereof;

FIG. 5 is a bottom plan view thereof;

FIG. 6 is a right side elevational view thereof;

FIG. 7 is a left side elevational view thereof;

FIG. 8 is a perspective view thereof, with the plugs in a use position; and,

FIG. 9 is a perspective view thereof, with the plugs in an alternative use position.
